UNITED STATES PATENT OFFICE.

DAVID H. MOSS, OF NEWARK, NEW JERSEY, ASSIGNOR TO BRANDES LABORATORIES, INC., OF NEWARK, NEW JERSEY, A CORPORATION OF NEW JERSEY.

DESIGN FOR A CASING FOR A PHONOGRAPH LOUD-SPEAKER UNIT.

Application filed August 21, 1925. Serial No. 14,544. Term of patent 14 years.

To all whom it may concern:

Be it known that I, DAVID H. Moss, a citizen of the United States of America, residing in Newark, county of Essex, and State of New Jersey, have invented a new, original, and ornamental Design for a Casing for a Phonograph Loud-Speaker Unit, of which the following is a specification, reference being had to the accompanying drawing, forming part thereof.

The figure is a perspective view of the casing for a phonograph loud speaker unit showing my new design.

I claim:

The ornamental design for a casing for a phonograph loud speaker unit, as shown.

DAVID H. MOSS.
